UNITED STATES PATENT OFFICE.

CARL BIRKENHAUER, OF BARMEN, GERMANY.

SINGLE-THREAD LACE-BRAIDING MACHINE.

Application filed August 30, 1921. Serial No. 497,072.

(GRANTED UNDER THE PROVISIONS OF THE ACT OF MARCH 3, 1921, 41 STAT. L. 1313.)

To all whom it may concern:

Be it known that I, CARL BIRKENHAUER, a citizen of the German Empire, residing at Barmen, Germany, 18 Wuppermannstrasse, have invented certain new and useful Improvements in Single-Thread Lace-Braiding Machines (for which I have filed applications for patent in Germany on September 9, 1919, Patent 396,339; England, September 20, 10 1920, Patent 174,671; Switzerland, March 31, 1921, Patent 98,529; France, March 29, 1921, Patent 533,369; Italy, March 30, 1921, Patent 301/1213; Holland, March 24, 1921, Patent 11,255; Belgium, March 31, 1921, 15 Patent 295,263; Czechoslovakia, March 29, 1921, application P. 2307/21), of which the following is a specification.

This invention relates to lace braiding machines of the kind in which there is one 20 bobbin for each driver, i. e. to so-called single thread lace braiding machines.

The invention deals with the long known problem of producing machines whose carriers are arranged to turn to the right and 25 left and whose drivers are arranged in a circle or similarly. This problem is solved by associating special guide members with the arrangement that renders it possible to turn the drivers to the right or left. These 30 guide members are made to move into and away from the carrier track and when they are moved in they prevent the carriers from leaving the driver on which they are to travel. The specific manner of accomplishing this in accordance with the invention 35 consists in certain guide members which, in conjunction with the neighbouring drivers, form circular tracks, being moved out of the planes of the feet of the carriers when 40 the carrier drivers are brought into engagement with the driving gear by which they are rotated to the right or left. The said guide members for two neighbouring drivers may be combined in one piece and the 45 edges of the guiding portions of the guide members and of the feet of the carriers may be bevelled.

Arrangements are also made by which the coupling members which give rise to right 50 hand or left hand motion can only be thrown out of gear at the moment the particular driver has completed the desired rotation even though the jacquard mechanism

may have previously ceased to exert its pull. The coupling of the driver with the various 55 rotating driving wheels may be effected in one and the same direction by means of jacquard apparatus, and the guide member may be arranged to be indirectly moved out of the track of the carriers whenever one 60 of the two jacquard pulls operates.

Another feature of the invention consists in one of the driving wheels for operating the driver being mounted on a special sleeve which prevents the driving wheel from imparting undesired rotation to the driver. The sleeves may be attached to small standards which also have parts that maintain the coupling in its position of engagement until the driver has reached its proper position. 70

A constructional form of the invention is shown in the drawing in which

Fig. 1 is a section through a driver associated with its coupling and holding devices and adapted to be rotated to the right and left. 75

Fig. 2 is a side view of Fig. 1 observed in the direction of the arrow.

Fig. 3 is a plan view of the track plate. 80

Fig. 4 is an elevation of the assembled machine with all its accessories.

Fig. 5 is a plan view of the machine according to Fig. 4 showing the direction of movement of the driving wheels. 85

Figs. 6 and 7 show different ways of driving the toothed wheels arranged to be brought into gear with the drivers.

Fig. 8 is a perspective view of a movable guide member. 90

The drivers 1 of the machine are located in the track plate 2 and have recesses each of which has two driving edges 3. Each driver 1 is rigidly connected or integral with a sleeve 4 associated with coupling members 95

5 and 6 adapted to move up and down on the sleeve whilst being prevented from rotating around the same. To this end the sleeve 4 is made with corners as shown in Fig. 3. The coupling member 5 is adapted to engage with the clutch of the toothed wheel 7 and the coupling member 6 is arranged to engage with the clutch of the toothed wheel 8. As indicated by the arrows the direction of rotation of the toothed wheel 7 is the reverse of that of the toothed 100 105

wheel 8 so that the driver 1 is rotated in different directions according as the coupling member 5 or 6 is thrown into gear with its corresponding toothed wheel 7 or 5 8 respectively.

The coupling member 5 (Figs. 1 and 2) is in engagement with a fork 9 which has a sleeve-shaped portion 9^a that is fixed by a screw to the rod 10 so that, on a downward 10 pull being exerted on this rod by means of the jacquard apparatus, the coupling member 5 is moved by the fork 9 into engagement with the toothed wheel 7. After the fork 9 has travelled downward a certain distance 15 its sleeve strikes against the lateral projection 11 of a sleeve 12 which is adapted to move up and down and has a plate 13 (Fig. 2) with an upwardly extending projection 14. This projection 14 is adapted to 20 enter into the notches 17 in a disk 15 fixed by screws 16 (Fig. 1) to the driver 1. When the projection 14 enters a notch 17 the driver 1 is prevented from executing an undesired 25 rotary movement around its axis.

25 The sleeve 12 is arranged to move up and down on the rods 18 and 10.

Arranged at the right of Fig. 1 is a standard 19, provided with projections 20 and 30 21 that protrude into recesses 22 and 23 in the coupling members 5 and 6 respectively, and which permit of downward movement of the coupling members 5 and 6 when the said recesses are located above the projections 20 and 21.

35 By the pull exerted by means of the jacquard apparatus on the rod 10 the coupling member 5 is first moved down until the projection 20 has passed through the recess or notch 22 in the upper annular ridge of the coupling member 5 and then the sleeve 9^a of the fork strikes against the located projection 11 of the sleeve 12 and at the same time the teeth of the coupling member 5 come into engagement with the clutch of the 40 toothed wheel 7, and the upwardly extending projection 14 leaves the cavity 17 and the guide member 13 moves out of the path of the foot 33 of the carrier.

When the pull exerted by means of the 45 jacquard apparatus ceases the coupling member 5 is retained in its position of engagement by the projection 20 until one of the notches 22 appears beneath the said projection, when the spring 24 will be able to 55 push the rod 10 with the arm 9, and therefore the coupling member 5 upwards.

The rod 10 is provided with a pin 25 to enable it to be operated by the spring 24. The lateral projection or arm 11 of the 60 sleeve 12 and the plate 13 with the projection 14 are pushed upwards by a spring 26 when the pull exerted by the jacquard apparatus ceases.

The engagement of the coupling member 65 6 with its corresponding clutch is effected

by a forked arm 28 projecting from a sleeve 27 fixed by a screw to the rod 18. When a pull is exerted on the rod 18 by means of the jacquard apparatus the part 12 is moved downward by a collar 29 after the projection 70 21 has passed through the notch 23 in the upper annular ridge of the coupling member 6. At the same time the projection 14 is moved downward so as to leave the corresponding recess 17 in the disk 15. 75

When the pull exerted by means of the jacquard apparatus ceases the parts 27, 28 and the coupling member 6 are moved upward by a spring 30 and restored to their normal positions as soon as the notch 23 80 appears beneath the projection 21. In this case also the part 12 is restored to its normal position by the spring 26.

As will be seen from Fig. 1 the toothed wheel 7 is arranged on a sleeve 31 supported 85 by the pillar 19. By this arrangement the toothed wheel 7 is prevented from imparting undesired rotary motion to the driver which might happen if the toothed wheel 7 were directly journaled on the pillar. 90

In addition to the upwardly extending projections 14 the parts 13, Fig. 3, have curved portions 32 which, in conjunction with their neighboring disk, form a complete circular track when the plate 13 is in 95 its raised position. It is thus seen that when the plate 13 is drawn down the carriers are enabled to rotate upon the driver corresponding to the said downwardly moved plate whilst their access to the neighbouring 100 driver is prevented by the curved portions 32 of the neighbouring plates on account of these curved portions still being in their raised positions. The curved parts 32 are preferably bevelled so that the carriers will, 105 if necessary, slide off these parts when the plate 13 is raised and move in between two neighboring plates 13. The foot 33, Fig. 2, of the carrier may be made conical for 110 the same purpose.

In Fig. 4, 34 is a belt pulley by which the machine is driven. This pulley rotates a gear wheel 35 (Fig. 5) which drives a large toothed wheel 36 by which toothed wheels 37^a, 37^b are rotated. The toothed wheel 37^a 115 transmits its motion to a set of lower wheels 8 (Figs. 5 and 6) whilst the toothed wheel 37^b imparts its motion to a set of upper wheels 7 (Figs. 5 and 7). By this means the upper wheels of each driver are rotated in the 120 opposite direction to the wheels of the lower drivers.

I claim—

1. In a lace braiding machine, a plurality 125 of rotatable and arrestable carrier drivers adjacent to each other, means for rotating the drivers each clockwise and counterclockwise, and guide members adapted to be moved into and out of the path of the carriers so as to keep the carriers in engagement 130

with the operating drivers and to prevent the carriers from travelling into the path of a driver adjacent an operating driver.

2. In a lace braiding machine, a plurality of rotatable and arrestable carrier drivers adjacent to each other, means for rotating the drivers clockwise or counterclockwise, guide members adapted to be moved into and out of the path of the carriers so as to keep the carriers in engagement with the operating drivers and to prevent the carriers from travelling into the path of a driver adjacent an operating driver, and a jacquard apparatus for operating the said guide members.

3. In a lace braiding machine, a plurality of rotatable and arrestable carrier drivers adjacent to each other arranged on a circle, means for rotating the drivers each clockwise and counterclockwise, the drivers having driving edges which are at equal distances from a middle line, and guide members adapted to be moved into and out of the path of the carriers, so as to keep the carriers in engagement with the operating drivers and to prevent the carriers from travelling into the path of a driver adjacent an operating driver.

4. In a lace braiding machine, a track plate for supporting the rotatable and arrestable carriers, a plurality of carrier drivers adjacent to each other, means for rotating the drivers each clockwise and counterclockwise, the top surface of the carrier drivers being flush with the track plate, and guide members adapted to be moved into and out of the path of the carriers, so as to keep the carriers in engagement with the operating drivers and to prevent the carriers from travelling into the path of a driver adjacent an operating driver.

5. In a lace braiding machine, a plurality of rotatable and arrestable carrier drivers adjacent to each other, means for rotating the drivers each clockwise and counterclockwise, and guide members movable in the direction of the axis of the carrier drivers adapted to be shifted into and out of the path of the carriers so as to keep the carriers in engagement with the operating drivers and to prevent the carriers from travelling into the path of a driver adjacent an operating driver.

6. In a lace braiding machine, carriers, a plurality of rotatable and arrestable carrier drivers adjacent to each other, means for rotating each of said drivers clockwise or counterclockwise, guide members movable in the direction of the axis of the carrier drivers adapted to be shifted into and out of the path of the carriers, so as to keep the carriers in engagement with the operating drivers and to prevent the carriers from travelling into the path of a driver adjacent an operating driver, and means for

pushing the carrier away from the guide members when the latter are moved.

7. In a lace braiding machine, carriers, a plurality of rotatable and arrestable carrier drivers adjacent to each other, means for rotating the drivers each clockwise and counterclockwise, guide members movable in the direction of the axis of the carrier drivers adapted to be shifted into and out of the path of the carriers, so as to keep the carriers in engagement with the operating drivers and to prevent the carriers from travelling into the path of a driver adjacent an operating driver, and bevelled parts on the guide members.

8. In a lace braiding machine, carriers, a plurality of rotatable and arrestable carrier drivers adjacent to each other, means for rotating the drivers each clockwise and counterclockwise, guide members movable in the direction of the axis of the carrier drivers adapted to be shifted into and out of the path of the carriers, so as to keep the carriers in engagement with the operating drivers and to prevent the carriers from travelling into the path of a driver adjacent an operating driver, and bevelled parts on the foot of the carriers.

9. In a lace braiding machine, rotatable and arrestable carrier drivers adjacent to each other, driving members for driving a plurality of said carrier drivers each in opposite directions, coupling means for connecting the carrier drivers with the driving members, and a single guide member for a carrier driver adapted to be moved into the path of the carriers and out of the path of the carrier whenever the driver is coupled for clockwise or counterclockwise rotation.

10. In a lace braiding machine, a plurality of rotatable and arrestable carrier drivers adjacent to each other, means for rotating the drivers each clockwise and counterclockwise, a guide member associated with a carrier driver and adapted for keeping carriers in engagement with operating drivers, means for moving the guide member out of the path of the carriers, and springs for returning the guide member to its initial position.

11. In a lace braiding machine, rotatable and arrestable carrier drivers adjacent to each other, driving members for rotating a plurality of said carrier drivers each in opposite directions, clutches for coupling the carrier drivers with the driving members, springs for restoring the clutches to their initial positions, guiding means associated with a carrier driver adapted for keeping the carriers in engagement with the operating drivers, means for moving the guide member out of the path of the carriers, and springs for returning the guide member to its initial position.

12. In a lace braiding machine, rotatable

4
and arrestable carrier drivers adjacent to each other, driving members for rotating a plurality of said carrier drivers each in opposite directions, coupling means for connecting the carrier drivers with the driving members, a single guide member for a carrier driver adapted to be moved into the path of the carrier and out of the path of the carrier whenever the driver is coupled for clockwise or counterclockwise rotation, and a single spring for restoring the guide member to its initial position.

13. In a lace braiding machine, a plurality of rotatable and arrestable carrier drivers adjacent to each other, driving members for rotating the carrier drivers each in opposite directions, clutches for coupling the carrier drivers with the driving members, jacquard apparatus for operating the said clutches, means for disengaging the coupling members only after they have been driven into an arresting position, and a movable guide member associated with a carrier driver adapted for keeping the carriers in engagement with an operating driver.

14. In a lace braiding machine, rotatable and arrestable carrier drivers, driving members for rotating each of a plurality of adjacent carrier drivers in opposite directions, guide members adapted to be moved into and out of the path of the carriers and arresting means associated with the said guide members for keeping the carrier drivers stationary.

15. In a lace braiding machine, rotatable and arrestable carrier drivers, driving wheels for rotating the carrier drivers in opposite directions, two clutches for each carrier driver for coupling it with either one of two said oppositely rotating wheels, and a movable guide member associated with a carrier driver adapted for keeping the carriers in engagement with an operating driver.

16. In a lace braiding machine, a plurality of carrier drivers adjacent to each other, driving members for rotating the drivers each in opposite directions, clutches for coupling the drivers with the driving members, jacquard apparatus for operating the said clutches, a movable guide member associated with each said driver and adapted to keep the carriers in engagement with an operating driver, and means for moving said guide member out of the path of the carriers each time said clutch is coupled.

17. In a lace braiding machine, a plurality of rotatable and arrestable carrier drivers adjacent to each other, driving members for rotating the carrier drivers each in opposite directions, clutches for coupling the carrier drivers with the driving members, jacquard apparatus for operating the said clutches, a holding member for keeping the clutches in engagement after the jacquard apparatus ceases operating

until the driver has reached a normal position, and a pillar for supporting the said holding member.

18. In a lace braiding machine, a plurality of rotatable and arrestable carrier drivers adjacent to each other, driving members for rotating the carrier drivers each in opposite directions, clutches for coupling the carrier drivers with the driving members, jacquard apparatus for operating the said clutches, a holding member for keeping the clutches in engagement after the jacquard apparatus ceases operating until the driver has reached a normal position, a pillar for supporting the said holding member, and a guide member associated with a carrier driver adapted for keeping the carrier in engagement with an operating driver.

19. In a lace-braiding machine a plurality of rotatable and arrestable carrier drivers adapted to be rotated clockwise and counterclockwise, two driven toothed wheels one above the other for each driver, a toothed driving wheel, an intermediate toothed wheel between the driving wheel and the said upper one of the said driven wheels, and a second intermediate toothed wheel between the driving wheel and the lower one of said driven wheels.

20. In a lace braiding machine, a plurality of carrier drivers adjacent to each other, driving members for rotating the drivers each in opposite directions, clutches for coupling the drivers with the driving members, jacquard apparatus for operating the said clutches, a movable guide member associated with a driver, adapted to keep the carriers in engagement with an operating driver, means for moving said guide member out of the path of the carriers each time said clutch is coupled, and other means for restoring the clutch and the guide member to their normal positions when the driver has reached its normal position.

21. In lace braiding machine, a plurality of carrier drivers adjacent to each other, driving members for rotating the drivers each in opposite directions, clutches for coupling the drivers with the driving members, jacquard apparatus for operating the said clutches, a movable guide member associated with a driver, adapted to keep the carriers in engagement with an operating driver, means for moving said guide member out of the path of the carriers each time said clutch is coupled, and other means for separately restoring the said clutch and the guide members to their normal positions when the driver has reached its normal position.

In testimony whereof I have affixed my signature.

CARL BIRKENHAUER.
